CHARLES B. HATFIELD, OF PHILADELPHIA, PENNSYLVANIA, ASSIGNOR
TO NORMAN M. KERR AND B. W. BEESLEY, OF SAME PLACE.

Letters Patent No. 67,050, dated July 23, 1867.

MACHINE FOR MAKING PAPER BOXES.

The Schedule referred to in these Letters Patent and making part of the same.

TO ALL WHOM IT MAY CONCERN:

Be it known that I, CHARLES B. HATFIELD, of the city and county of Philadelphia, in the State of Pennsylvania, have invented a new and useful Improvement in Machinery for Making Paper Boxes, of which the following is a full, clear, and exact description, reference being had to the accompanying drawings, which make part of this specification, and in which—

Figure 1 represents a plan or top view of my improved machine, the red lines showing the sliding frame as retracted.

Figure 2 represents a view in elevation of the same, as seen from the front, the red lines showing the head-holder in contact with the chuck.

Figure 3 represents a face view of the head-holder, and

Figure 4 a similar view of the holding-chuck.

It is well known to paper-box manufacturers that boxes, the tops and bottoms of which project beyond the cylindrical body, have hitherto been so expensive and difficult to finish neatly that they have been imported from France, and have thus come to be designated as "French-edge boxes."

It is the object of my invention to finish by machinery paper boxes called technically "French-edge boxes," and I therefore call this machine the "French-Edge Machine."

My said improvement consists, first, in a chuck or head (to receive and carry the sides or body of the box) rotating in a fixed relation to but projecting beyond its supporting-frame so as to leave room for putting the box on and taking it off without moving the head; second, in combining with a rotating holding-chuck a device for discharging the box when formed; third, in a vibrating head-holder for receiving the box-head and holding it against the holding-chuck which carries the body of the box; fourth, in combining a vibrating head-holder with a vibrating holding-frame so arranged that when the holder has been forced against the chuck the frame is withdrawn to leave room for the other parts of the mechanism to advance; fifth, in a flanged former or head mounted in a sliding frame, and rotated by its pressure against the holding-chuck, to paste the strip on the box and to turn over the edge of the paper to unite the head and sides of the box; sixth, in so combining a rotating fixed chuck, a rotating traversing former, and a vibrating head-holder that the sides and head of the box are united by one continuous operation.

A paper box consisting of two parts, a top and bottom, the one being a counterpart of the other, I speak of the head and sides only, for convenience, it being obvious that the bottom and sides are made by the same process exactly, and that one expression may be used indifferently for both.

In the accompanying drawings, which show one convenient way of carrying out the objects of my invention, the holding-chuck A for receiving the body of the box is shown as rotating on one end of a shaft, R, turning in proper bearings in a strong frame, P. The forming-chuck or presser-head B is formed with a flange, b, on its outer edge, and with a groove, b', between the head and flange, as shown in the drawings, and is mounted on one end of a shaft, S, rotating in proper bearings in a frame, C, which slides on the frame P. A coiled spring, Y, on the shaft S, keeps the presser-head B drawn in towards the frame so that its flange may press against the face of the chuck A, and yet allow it to yield enough to accommodate the thickness of the head of the box. The sliding-frame C is retracted by a cord, L, passing over a pulley, J, and connected to a foot-lever, L'. It is drawn forward again by springs c. A vibrating head-holder or disk-receiver, F, is hinged to the frame at T, so as to swing towards and from the chuck A, against which, when thrown up, it is held by a catch, a, and spring detent b'. The head-holder F is drawn down when released by a spring, s, at its back. This receiver F may be of any size or form requisite for the particular box being finished. This holder when drawn down rests in a vibrating holder-frame, E, hinged concentrically with holder F, and is pressed outward from the frame by a spring, d. The presser-off consists of a series of ribs, p, arranged radially and parallel to the axis of the shaft R upon a ring, P', which rotates with the axis, being pressed outwards by the lever X and inwards by a coiled spring, X', fig. 2. These ribs work endwise through radial slots in the chuck A to press off the box when finished.

The operation of the machine is as follows: The parts being in the position shown in fig. 1, the operator places the disk to form the top or bottom of the box (which disks have been cut to a proper size) in the head-

holder G, which forms part of the disk-receiver F. The sliding-pieces m can be moved in or out to adapt the holder E to receive disks of varying sizes. The sliding-frame C having been retracted, the ring forming the sides of the box (which has been already formed) is then slipped on the chuck A, its inner edge resting on the shoulders of the presser-off P'. The holder E, with the receiver F, carrying the top of the box, is then struck up against the face of the chuck A by a smart blow from the hand of the workman; the spring detent b' catches in the hook a and holds the disk-receiver F with the box-head firmly against the face of the chuck A, while the holding-frame E flies back to its original position. One end of a properly-glued or pasted strip of paper somewhat wider than the height of the box is then placed on the ring on the chuck, and by means of the crank-handle D the chuck is turned about a quarter of a revolution. The frame C is then released and its spring presses the former B against the chuck A. The continuous rotation of the chuck A causes the glued strip to adhere to the ring on the chuck, while the presser-roller or former B presses it out smoothly, and the flange b turns the projecting edge of the paper strip over and presses it against the disk or head, thus uniting the two securely. The projecting rim of the box enters the groove b' on the former, and is thus protected from injury. The frame C is now retracted and the holder F released, when it flies back to its position in the holder-frame E. The lever X is then moved outward from the frame and presses the box off the chuck A, when everything is ready for a repetition of the operation above described.

It will thus be seen that by my invention I am enabled to use a chuck revolving in a fixed position; to obtain ample room for applying the ring thereto; that the holder keeps the disk securely in place, and that the retracting former leaves room at the proper time for the vibrating holder-frame to work, and unites the top and sides of the box smoothly and securely.

By a mere adaptation of form in the receiver F square boxes or oval boxes may be made in the manner herein described, the skill of the operator being all that is requisite in working it, and I do not, therefore, confine myself to round boxes.

What I claim as my invention, and desire to secure by Letters Patent in a machine for finishing "French-edge paper boxes, is—

1. A chuck or box-holder, A, arranged to rotate in a fixed position outside of the frame P, substantially as described.
2. The combination, substantially as described, of a slotted chuck rotating in a fixed position, with a presser-off rotating concentrically with the chuck, having an endwise motion on its axis.
3. A vibrating head-holder or disk-receiver, arranged substantially as described, for the purpose of holding the disk to form the head of the box against the ring constituting its sides.
4. The combination, substantially as and for the purpose described, of a vibrating disk-receiver or head-holder, with a vibrating holding-frame.
5. The combination of the chuck A, flanged and grooved former B, and sliding-frame C, when arranged and operating substantially as described.
6. The combination, substantially as described, of a chuck rotating in a fixed position outside the frame, a rotating former mounted in a traversing-frame, and a vibrating head-holder or disk-receiver, for the purpose of uniting the head and sides of the box by a single continuous operation.

In testimony whereof I have hereunto subscribed my name.

C. B. HATFIELD.
